(57) **CLAIM**

The ornamental design for a drilling and driving tool, as shown and described.

DESCRIPTION

FIG. 1 is a front left perspective view of the present new design for a drilling and driving tool;

FIG. 2 is a left elevational view thereof;

FIG. 3 is a right elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines showing various features of a drilling and driving tool that is configured to receive a driving bit are for illustrative purposes only and form no part of the claimed design.
